HIGH FREQUENCY SIGNALING APPARATUS

Louis A. Gebhard, Washington, D. C.

Application January 27, 1933, Serial No. 653,885

20 Claims. (Cl. 250—17)

(Granted under the act of March 3, 1883, as
amended April 30, 1928; 370 O. G. 757)

My invention relates broadly to signaling systems and more particularly to a high frequency transmitting system.

One of the objects of my invention is to provide a construction of high frequency signal transmitting apparatus which is efficient in its construction and simple in its manufacture and assembly.

Another object of my invention is to provide a construction of high frequency signal transmitting apparatus wherein the length of the leads interconnecting the inductance system with the electron tube elements employed in the transmission circuits are reduced to an absolute minimum for improving the efficiency of the transmitter.

Still another object of my invention is to provide a construction of high frequency signal transmission apparatus in which electron tubes of the high power type are mounted concentrically with the axes of the tuning inductance units and adjustment of inductance obtained by contactors which move in paths immediately below the high power tubes in positions requiring minimum length of leads between parts of the high frequency circuits.

A further object of my invention is to provide a construction of high frequency signal transmitting apparatus in which fluid cooled electron tubes are employed and the fluid cooled inductances associated with the fluid cooled tubes in positions adjacent the fluid cooled tubes and a fluid path of a minimum length provided through the fluid cooled tubes and the inductances for insuring operation of the apparatus at maximum efficiency.

A still further object of my invention is to provide a high frequency signal transmitting system including electron tubes and high frequency inductance units so associated as to provide maximum inductance with minimum external field and minimum coupling to other parts of the system.

Another object of my invention is to provide an arrangement of cooling fluid system for balanced high frequency electron tube circuits in which inductance units are concentrically disposed along the axes of the electron tubes and cooling fluid so distributed as to insure maximum cooling operation with minimum radio frequency losses.

Other and further objects of my invention reside in the compact assembly of high frequency signaling apparatus for the efficient transmission of signals over a predetermined range of frequencies as will be set forth more fully in the

specification hereinafter following by reference to the accompanying drawings, in which:

Figure 1 is a side elevation of the inductance system employed in the transmitter of my invention and showing the relation of the inductance system to the high power tubes employed in the transmitting circuit; Fig. 2 is a bottom plan view of the inductance system employed in the transmission apparatus of my invention; Fig. 3 is a transverse sectional view taken through the inductance system on line 3—3 of Fig. 4; Fig. 4 is an elevational view of the inductance system illustrating the association thereof with the high power tubes and showing parts of the inductance system in cross section for illustrating the adjusting means by which the frequency of operation of the apparatus is predetermined; Fig. 5 is a wiring diagram illustrating the electrical connection of the apparatus in the system of my invention; and Fig. 6 is a schematic view showing the path of the fluid cooling medium through the inductance units and around the anodes of the high power tubes in the system of my invention.

In a radio transmitter having a high power output, it is important that the efficiency of the circuit be as high as possible. To this end it is necessary that the output circuit of the high power amplifier be arranged to have the proper L/C ratio. It is very simple to do this at low frequencies. At high frequencies, however, the capacities in the circuit provide capacity reactances which are so low that it is difficult to obtain the proper L/C ratio and still cover a wide frequency band. The use of inductive tuning rather than capacitative tuning permits operation of the transmitter over a wide frequency band. The inductance, however, should be varied by cutting it out of the circuit in a continuously variable arrangement so as to give continuous variation of frequency. To go up as high as possible in frequency, the system must be so arranged that a minimum of inductance remains in the circuit. The output circuit of a high power amplifier involves a still further problem in design. This is the introduction of a cooling fluid to maintain the anode of the high power tube and the inductance system at the proper temperature. The system shown in the accompanying figures meets these requirements.

In order to reduce the amount of the inductance in the circuit at minimum position, the liquid cooling jackets 1 and 1' containing the electron tubes 2 and 2' are mounted coaxial with and on top of the inductance coils 3 and 3'. The

inductance coils are made up of a conductor shown in cross section in Fig. 4 having two fluid cooled paths, but a single electrical path. This conductor is supported by insulating members 5 and 5' from longitudinal supports 6 and 7. The variation of inductance of the coil is secured by the use of a brush 8 rotating over the outer surface of a tube 9 driven by gear 10. Tube 9 rotates about a fixed cylinder 11 containing in its outer surface a spiral square shaped thread 12. Cylindrical member 13 holds brush 8 about tube 9. The upper end of cylindrical member 13 is provided with a multiplicity of slots for increasing the resiliency of the sleeve like portion of member 13 for providing a good connection with tube 9. A combination screw and pin 14 screws into member 13 and passes through a longitudinal slot 50 in tube 9 into the square thread in the outer surface of 12. The rotating of tube 9 causes the rotation of brush 8 as well as imparting sliding movement longitudinally of the inductance to conform to the pitch of the coil. Gear 10 is attached to tube 9 and is driven by worm 15 through insulating members 16 and 17 from a crank 18 mounted on the front panel 19 of the radio transmitter. A counter mechanism 20 is provided to indicate the adjustment. Inside of tube 11 is located another tube 21 which passes into the lower end of the shaft and extends upward into the jacket 1. The lower ends of coil 3 are connected through tubes 22 and 23 respectively to the space between tubes 21 and 11 and to the lower end of tube 21.

The two halves of the system are symmetrical and connected together at point 24. An inlet 25 and an outlet 26 are provided for the cooling fluid. An electrical connection is also made at this point so that the positive anode potential may be fed in from the power source as shown in Fig. 5. It should be noted that the turns of the two coils are wound in the same direction so as to provide maximum inductance with minimum external field and minimum coupling to other parts of the system.

Fig. 6 shows the fluid cooling circuits of the system of my invention. The cooling fluid enters the system at 27, passes up through the insulating hose coil 28 into the inductance system at 25 where it divides so as to pass into coils 3 and 3'. It enters these coils at the top, (Fig. 4) passes through the conductor through tubes 23 and 21 into the fluid jacket 1. In the jacket the cooling fluid passes over the surface of the anode to the top, returning through discharge outlet 29 down to the space between tubes 21 and 11 through tube 22 up back through the conductor to outlet 26 through the insulating hose coil 30 discharging at 31.

Fig. 5 shows the electrical connections of the system. With the structural arrangement shown, it will be seen that the shaft of the coil is directly connected through the jacket 1 to the anode of the electron tube. This connection is a very short one. When the brushes 8 are at the top of the coil, the only inductance in the circuit is through the brushes to connection 24 which is extremely short. It will be seen that the unused portions of the coil, which are the lower portions, are short circuited. Since the system contains two short circuited portions in the two halves of the system, the possibility of setting up resonant currents in these short circuited portions is a minimum. Their natural period is at a very high frequency beyond the frequency range of the transmitter. If desired, condenser 32 may

be connected in parallel with the inter-element and distributed capacities of the circuit to augment the frequency range of the transmitter. The electron tubes 2 and 2' are shown in this figure as four element tubes with a screen grid connection. I may employ three element tubes in the usual push-pull balance system. Fig. 5 shows an amplifier circuit where the input is at 33 and the output at 34. The simultaneously controlled condensers 35 and 35' are provided for coupling adjustments.

The input inductance is provided with adjustable taps represented at 33a and 33b movable over inductance 33 for including the required number of turns in the circuits leading to the control grids 2a and 2'a of electron tubes 2 and 2'. The input circuits are completed through choke coil 36 and source of grid biasing potential connected to terminals 37 across bypass condenser 38 leading to the midpoint 39 in the secondary winding of the filament heating transformer 40. The cathode heating energy for the cathodes 2b and 2'b is supplied from transformer 40. The plate potential is connected across terminals 41 across which the bypass condenser 42 connects. The plate circuit is completed as illustrated by the connection which leads to terminal 24 through inductance units 3 and 3' to the anodes 2c and 2'c as shown. The potential for energizing the screen grids 2d and 2'd is derived from sources which connect across terminals 43 and 44. Bypass condensers 45 and 46 are arranged across the potential sources 43 and 44 as shown. Suitable balancing condensers 47 are connected in the cathode circuit as shown. The extension of the frequency over which the transmitter may be adjusted is accomplished by the connection of condenser 32 through contacts 32a and 32b with the inductances 3 and 3'. Intermediate adjustments of frequency may be effected by movement of brushes 8 along the turns of the inductances 3 and 3'.

The arrangement of the electrical paths through the inductance units and the fluid cooling paths through the inductance units is such that the fluid cooling paths are arranged in parallel through the inductance units while the electrical paths through the independent inductance units are in series between the individual anodes and the source of potential. The cooling fluid supplied through inlet 27 passes in the opposite direction from the connection at 25 through each of the inductances 3 and 3'. The circulating fluid after it passes through electron tube jackets 1 and 1' by passing through conductors 23 and 23' and upwardly through tubes 21 and 21' is returned from electron tube jackets around the annular spaces intermediate tube 21 and tube 11, circulating through the twin conductor constituting the other part of the duplex inductance units 3 and 3' to the outlet 26 where it is discharged through hose coil 30 and discharge pipe 31. The distribution of cooling fluid through the inductance units is, in this way, effected in parallel arrangement while the electrical circuits through the inductance units are established in independent series paths constituting the output circuits of the separate electron tubes.

By reason of the inherent shortness of the leads in the transmitting apparatus of my invention and the compact arrangement of the inductance and electron tube units, a transmitter of high efficiency is obtained. The parts of the apparatus are so arranged as to be readily

replaceable and accessible for the making of the required repairs.

While I have described my invention in one of its preferred embodiments, I desire that it be understood that modifications may be made and that no limitations upon my invention are intended other than are imposed by the scope of the appended claims.

The invention herein described may be manufactured and used by or for the Government of the United States of America for Governmental purposes without the payment of any royalty thereon or therefor.

What I claim as new and desire to secure by Letters Patent of the United States is as follows:

1. Radio transmission apparatus comprising a fluid cooled electron tube socket having fluid inlet and discharge connections, a twin conductor fluid cooled inductance wound on an axis concentric with the axis of said socket and fluid passages extending from the lower ends of said twin conductor axially through said inductance and connected with said fluid inlet and discharge connections in said fluid cooled electron tube socket, and fluid inlet and discharge connections at the upper end of said twin conductor fluid cooled inductance.

2. In a high frequency signal transmission system, a set of electron tubes each having an axially extending electrode, inductance units individual to each of said electron tubes and having their axes disposed on the axes of said tubes, and fluid cooling means for the axially extending electrode of each of said electron tubes extending through each of said inductance units.

3. High frequency signaling apparatus comprising a fluid cooled electron tube apparatus having fluid inlet and discharge connections, an inductance unit disposed on an axis coincident with the axis of said electron tube structure, means extending through said inductance unit and adjustable to select the effective number of turns in said inductance unit, and means interconnecting said fluid cooled inductance with the inlet and discharge connections of said electron tube apparatus for effectively cooling both said electron tube apparatus and said inductance.

4. In a high frequency signaling apparatus, a frame structure, an electron tube fluid cooled jacket supported by said frame structure, tubular inlet and discharge connections depending from said electron tube jacket through said frame structure, a fluid cooled inductance concentrically disposed around said tubular inlet and discharge connections, and means operative within said fluid cooled inductance for controlling the effective number of turns in said inductance.

5. High frequency signaling apparatus comprising a frame structure, a fluid cooled electron tube jacket supported by said frame structure, concentrically disposed tubes depending from said fluid cooled jacket providing inlet and discharge paths for the circulation of cooling fluid to and from said electron tube jacket, a fluid cooled inductance concentrically mounted about said tubes, fluid inlet and discharge connections between said fluid cooled inductance and the lower portions of said tubes, and means operative within said inductance for controlling the effective number of turns thereof.

6. High frequency signaling apparatus comprising a frame structure, a fluid cooled electron tube jacket supported by said frame structure, concentrically disposed tubes depending from the lower portion of said jacket and providing paths

for the circulation of cooling fluid to and from said jacket, a twin conductor fluid cooled inductance concentrically mounted around said tubes, connections between the lower portions of said tubes and the lower ends of said twin conductor inductance, and means surrounding said tubes and angularly adjustable for controlling the effective number of turns in said fluid cooled inductance.

7. High frequency signaling apparatus comprising a frame structure, a fluid cooled electron tube jacket supported by said frame structure, concentrically disposed tubes depending from the lower portion of said jacket and providing paths for the circulation of cooling fluid to and from said jacket, a twin conductor fluid cooled inductance concentrically mounted around said tubes, connections between the lower portions of said tubes and the lower ends of said twin conductor inductance, a rotatable sleeve concentrically positioned about said tubes, a contact arm guided by said sleeve and establishing connection with the turns of said inductance, means for selectively revolving said contact arm, and fluid inlet and discharge connections at the upper end of said twin conductor inductance.

8. High frequency signaling apparatus comprising a frame structure, a fluid cooled electron tube jacket supported by said frame structure, concentrically disposed tubes depending from the lower portion of said jacket and providing paths for the circulation of cooling fluid to and from said jacket, a twin conductor fluid cooled inductance concentrically mounted around said tubes, connections between the lower portions of said tubes and the lower ends of said twin conductor inductance, a rotatable sleeve concentrically mounted on said tubes, a radially positioned arm carried by said sleeve and adapted to move in a spiral path along said inductance for selecting the effective number of turns in said inductance, and means for admitting and discharging cooling fluid at the upper end of said twin conductor fluid cooled inductance.

9. High frequency signaling apparatus comprising a frame structure, a fluid cooled electron tube jacket mounted on said frame structure, a pair of concentrically positioned tubes depending from said jacket and providing paths for the circulation of cooling fluid through said jacket, a spiral thread formed on the exterior of one of said tubes, a rotatable sleeve concentrically disposed upon the said last mentioned tube, an arm carried by said sleeve and having a member extending through said sleeve and engaging the screw threads formed on said last mentioned tube, a twin conductor fluid cooled inductance concentrically mounted about said sleeve, a sliding contactor carried by said arm and engaging the turns of said fluid cooled inductance, fluid inlet and discharge connections with the upper end of said twin conductor inductance, fluid inlet and discharge connections between the lower ends of said twin conductor inductance and the said tubes for providing a fluid circulating path through said inductance and through said fluid cooled jacket.

10. In a balanced amplifier circuit, a pair of fluid cooled electron tubes, fluid cooled jackets for each of said electron tubes, twin conductor fluid cooled inductance units individual to each of said electron tubes, means for simultaneously controlling the effective number of turns in said inductance units, fluid inlet and discharge connections for said inductance units, said inductance units, and the lower ends of said jackets.

- tance units being electrically connected through said fluid inlet and discharge connections and being disposed electrically in series with the output circuits of the respective electron tubes.
- 5 11. A balanced amplifier circuit comprising a pair of fluid cooled electron tubes, fluid cooled inductance units individual to each of said fluid cooled electron tubes, a fluid circulating system connected in parallel with each of said inductance units, means for simultaneously varying the effective number of turns in said inductance units, and circuits electrically connecting the respective inductance units in series in the output circuits of each of said electron tubes.
- 10 12. High frequency signaling apparatus comprising a frame structure, a pair of fluid cooled inductance units extending on axes parallel to each other, fluid cooled tube jackets disposed in alignment with the axes of said inductance units, fluid conducting members interconnecting said jackets with said inductance units, means for emitting and discharging cooling fluid to said inductance units for circulation therethrough and through said jackets and means for simultaneously controlling the effective number of turns in each of said inductance units.
- 15 13. High frequency signaling apparatus comprising a frame structure, a pair of fluid cooled jackets carried by said frame structure on vertically disposed axes parallel to each other, inductance units carried by said frame structure immediately below said jackets and on axes coincident with the axes of said jackets, and rotatable means extending through said inductance units for selecting the effective number of turns in said inductance units, said inductance units being constituted by hollow tubular conductors connected with said fluid cooled jackets and connected with fluid inlet and discharge terminals for effectively cooling said inductance units and said tube jackets.
- 20 14. High frequency signaling apparatus comprising a frame structure, fluid cooled electron tube jackets carried by said frame structure, fluid cooled inductance units mounted on said frame structure and disposed concentrically about the axes of said jackets, connections between said jackets and said fluid cooled inductance units for the circulation of cooling fluid therethrough, and means operative within each of said inductance units for short-circuiting the ineffective turns of said inductance units while establishing a separate series circuit through the effective turns of said inductance units.
- 25 15. In a balanced amplifier system, a pair of fluid cooled electron tube jackets, fluid cooled electron tubes mounted in said jackets, separate fluid cooled inductance units concentrically mounted with respect to each of said jackets and independently connected in series relation in the output circuits of the respective electron tubes, means for simultaneously controlling the effective number of turns in said fluid cooled inductance units, a tuning reactance, and means for electrically connecting said tuning reactance in parallel with said inductance units for extending the frequency range thereof.
- 30 16. A balanced amplifier comprising a pair of fluid cooled electron tubes, a fluid cooling jacket individual to each of said electron tubes, twin conductor inductance units concentrically mounted with respect to each of said jackets, tubular conductors interconnecting said jackets with the respective twin conductor inductance units, means for supplying and discharging cooling fluid to said cooling jackets through said inductance units, and circuit connections for establishing a series electrical path between the respective inductance units and the output circuit of each of said electron tubes.
- 35 17. Radio transmitting apparatus comprising a frame structure, a pair of fluid cooled electron tube jackets carried by said frame structure, inductance units each comprising a twin tubular conductor concentrically wound with respect to the axis of said jackets, connections between the lower ends of the twin conductors constituting said inductance units and said fluid cooling jackets, and connections between the upper ends of said twin conductor inductance units and fluid inlet and discharge terminals for effectively cooling both said inductance units and said jackets.
- 40 18. High frequency signaling apparatus comprising a frame structure, a pair of fluid cooled electron tube jackets carried by said frame structure, inductance units vertically mounted on said frame structure adjacent each of said electron tube jackets, said inductance units each comprising a twin tubular conductor having the elements thereof wound immediately adjacent each other, a fluid supply connection, a fluid discharge connection, a tubular conductor extending from said fluid supply connection to one conductor at the upper end of each of the said inductance units, a tubular conductor extending from said fluid discharge connection to the other conductor at the upper end of each of the said inductance units, and connections between the conductors at the lower ends of the respective inductance units and the fluid cooled electron tube jacket individual to that inductance unit.
- 45 19. A balanced amplifier system comprising a pair of electron tubes, fluid cooled jackets individual to each of said electron tubes, duplex tubular inductance units concentrically disposed with respect to each of said fluid cooled jackets, means for simultaneously varying the effective number of turns in said inductance units, fluid conveying conduits interconnecting said inductance units with said fluid cooled jackets, a fluid supply terminal, a fluid discharge terminal, and parallel electrical connections between said terminals and fluid distribution paths.
- 50 20. Radio apparatus comprising a frame structure, a fluid cooled electron tube jacket carried by said frame structure, fluid inlet and discharge connections for said jacket, a pair of concentrically disposed conduits connected with said fluid inlet and discharge connections, a duplex conductor inductance unit, insulation means carried by said frame structure and supporting the turns of said inductance unit concentrically with respect to said pair of concentrically disposed conduits, fluid supply and discharge connections between the lower ends of said duplex inductance unit and said conduits, and fluid supply and delivery connections with the upper end of said duplex inductance unit for providing a circulatory path through said duplex conductor inductance unit and through said fluid cooled jacket.

LOUIS A. GEBHARD.
